WINDOW DEVICE FOR GARMENT BAGS

William R. Kohl, Glenview, and Arden L. Iverson,
Chicago, Ill., assignors to Para-Lux Products
Company, Chicago, Ill., a corporation of Illinois

Application November 3, 1947, Serial No. 783,818

9 Claims. (Cl. 206—45.31)

1

This invention pertains to improvements in a simple, inexpensive and readily applied window device for paper bags, particularly of the type commonly employed in the delivery or storage of garments and the like after dry cleaning thereof. However, the principles of the invention are also adapted for application to containers of other types.

It is an object of the invention to provide a device of the foregoing character which is inexpensively manufactured in quantity lots, employing a minimum of material, which is readily and quickly assembled and applied to the garment bags, and which is easily manipulated in use.

Another object is to provide a normally sealed window device which, when applied in operative position over an opening in the garment bag or like container, functions to provide a light-tight and dust-tight closure of said opening, preventing soiling or fading of or other damage to a garment or other article in the container.

Yet another object is to provide a window device for containers which is characterized by a light-sealing flap hinged to the remainder of the device in a manner to enable said flap to be lifted when it is desired to view the contents of the container through an opening therein over which the device is applied, said flap having novel provisions for enabling the same to be replaced in covering relation to said opening and secured thereover against inadvertent displacement.

A still further object of the invention is to provide a garment bag window device having a closure flap of the foregoing type, in which said flap is arranged to substantially overlap marginal edges of an opening in the garment bag.

A still further object is to provide a device of the type referred to in the preceding paragraph, which incorporates a double ply layer of transparent material effective to prevent entry of dust through an opening in the garment bag before and after said closure flap is displaced from sealing relation to the window device and bag.

The foregoing statements are indicative in a general way of the nature of the invention, but other and more specific objects of the invention will be apparent to those skilled in the art upon a full understanding of the construction and operation of the device.

A single embodiment of the invention is presented herein for purpose of exemplification, but it will be appreciated that the principles of the

2

invention are susceptible of incorporation in still other modified forms coming equally within the scope of the appended claims.

In the drawings,

Fig. 1 is a fragmentary view in front elevation illustrating a window device in accordance with the present invention, as applied to a conventional garment bag or the like (indicated fragmentary), showing the device in the condition thereof prior to loosening and lifting of a closure flap thereof for the inspection of garments or other articles in the bag;

Fig. 2 is a view of the device itself in its flat condition, showing the internal parts of the same prior to folding and applying the device to the garment bag;

Fig. 3 is an enlarged fragmentary view in vertical central section through a wall of the garment bag and window device applied thereto, illustrating in solid lines the manner of swinging the closure flap of the device outwardly to enable inspection of the contents of the bag, and in dotted lines the manner of swinging the flap reversely to return and re-engage the same in operative sealing relation to the bag;

Fig. 4 is a fragmentary view in front elevation showing the mode of bending a locking tab of the aforesaid flap prior to engaging said tab in locking relation to the remainder of the device;

Fig. 5 is a front elevational view of the body of the device in its condition for the reception of the folded locking tab of Fig. 4;

Fig. 6 is a fragmentary view similar to Fig. 3 but showing the closure flap in closed position, being in vertical cross section along line 6—6 of Fig. 7; and

Fig. 7 is a fragmentary view in front elevation similar to Fig. 1, illustrating the relationship of the parts in the replaced and locked condition of the sealing flap of the window device.

The present invention affords a simple and inexpensive window device adapted to be readily and quickly applied to garment bags of well known types, or other related types of containers which are provided with an aperture in a wall thereof for the inspection of their contents. A portion of such a garment bag or container is fragmentarily illustrated in Figs. 1, 3 and 7 and is designated by the reference numeral 10. The window device per se is illustrated in Fig. 2 in its flat condition prior to final folding thereof and application to the bag 10, being generally designated by the reference numeral 11. Fig. 1 shows the device 11 in operative position on the

bag, but prior to manipulation of a flap of the device to expose the contents of the bag through an inspection opening 12 cut therein. Fig. 7 shows the condition of the parts after such manipulation, with the device operatively relocked in sealing relation to said window.

The window device as illustrated in blank form in Fig. 2, comprises an elongated, generally rectangular, two-panelled blank 13 of a suitable lightweight, flexible paperboard stock. This blank is subdivided transversely by a creased fold line 14 at approximately its medial point into outer and inner sections or panels 15, 16 respectively, of which the former is of substantially greater width and somewhat greater length than the latter.

The smaller panel 16 is provided with a cut-out aperture 17 in its approximate center which is spaced substantially inwardly of the end and side margins of said section and from the fold line 14. The larger panel 15 is provided with a generally U-shaped slit including side portions 18 paralleling and spaced substantially inwardly from the side margins of said panel, transversely extending portions 19 connected with said respective side portions and paralleling and spaced from the fold line 14, and the convergent neck portions 20 which approach the aforesaid fold line. The slitting of the blanks is completed by the inverted U-shaped, tab defining slit 21 which extends into the panel 16, crossing the fold line 14 into panel 16 at a point immediately adjacent the ends of curved slits 20. The ends of slit 21 are spaced slightly from but aligned with the adjacent ends of said slits 20, leaving the small increments of material 22 therebetween which are adapted to be torn readily.

The aforesaid slitting of panels 15, 16 affords a closure flap 23 normally sealing a similarly shaped inspection opening 24 of U-shaped outline in the panel 15. Said flap terminates at its free end in a locking tab 25 cut from the material of panel 16. Flap 23 is adapted for hinging movement about a line between the opposed in-turned termini 26 of slits 18.

An elongated rectangular sheet of flexible transparent window material such as cellophane, designated by the reference numeral 27, is applied over the aforesaid slitted and cut areas of the blank, in the fashion illustrated in Fig. 2, being adhered to the panels 15, 16 externally of the opening 17 and the slit 18 in a manner to seal the device against entry of dust through those cut portions.

With the window sheet so applied, the device is folded along the fold line 14 and adhesively secured around its border to the garment bag 10, care being taken that the aperture 17 in panel 16 registers with the inspection opening 12 in the wall of said bag. In folding the panels along line 14, the tab 25 is retained in the plane of its panel 16, by reason of the connection of the flap 23 to said panel by the small amounts of material at 22. The tab 25 laterally overhangs the lower margin of the device, represented by the fold line 14, as illustrated in Fig. 1, but may be readily engaged by a finger nail to tear the material at 22 and free flap 23 for outward swinging movement.

In the above condition, it will be noted that the flap 23 substantially overextends the margins of the opening 17 in panel 16 and the subjacent garment bag opening 12. It therefore effectively seals the bag against the entry of light apt to cause discoloration or fading of garments there-

in. The double thickness of cellophane disposed between panels 15, 16 further protects the interior against the entry of moths, dirt and foreign matter.

When it is desired to view the contents of the bag or other container through the openings 17, 12 the user merely pries tab 25 loose with a finger nail, rupturing the material at 22, whereupon said flap 23 may be swung upwardly from the position of Fig. 1 to the solid line position of Fig. 3, exposing said openings. In replacing the flap to sealing relation to the garment bag, the tab 25 is first folded rearwardly and upwardly along the portion of the creased fold line 14 which extends transversely thereacross onto the rear surface of the neck of the tab, i. e., from the solid line position of tab 25 in Fig. 3 to the dotted line position. This leaves the laterally extending ears 28 of said tab exposed on either side of the reduced neck of the flap 23, as illustrated in Fig. 4. It will be observed in Fig. 5 that the panel 15, adjacent the marginal fold line 14, now presents the laterally spaced retainer ears 29, so that it is only necessary for the user to buckle the flap outwardly and upwardly somewhat to enable the locking ears 28 of tab 25 to be slit downwardly and into the pocket behind said retaining ears 29, in the fashion illustrated in Figs. 6 and 7. The coaction of these locking and retaining ears thereafter serves to maintain closure flap 23 in its original sealing relation to the opening 17. Should it be desired to again remove the flap for viewing the garment bag contents, it is only necessary to slide the same upwardly 35 slightly whereby to disengage said ears and enable flap 23 to be again swung outwardly to the solid line position of Fig. 3.

The locking action provided by the foregoing parts is positive and displacement resisting. Furthermore, the folding of the flap on line 14 to displace tab 25 rearwardly has the effect of reinforcing and stiffening the flap at this point against bending about a vertical axis. As a result, the flap is only removed from the locking engagement thereof with panel 15 by the aforesaid upward sliding movement. It cannot be released inadvertently.

What we claim is:

1. A window device for a container having an inspection opening therein, said device comprising a pair of inner and outer panels adapted to be secured to said container in superposed relation to one another over said opening, one of the panels having an aperture therein and the other being cut to provide a closure flap hingedly connected thereto, said flap overlapping the adjacent margin of the device in the superposed relation of the panels and of said aperture and opening, and having an integral lateral locking enlargement thereon to hold the flap in sealing relation to said aperture and opening.

2. A window device for a container having an inspection opening therein, said device comprising a flexible fibrous member subdivided by a transverse fold line into a pair of inner and outer panels adapted to be secured to said container in superposed relation to one another over said opening, one of the panels having an aperture therein and the other being cut to provide a closure flap hingedly connected thereto, said flap overlapping said fold line when said member is folded thereon to the superposed relation of the panels and of said aperture and opening, and provided with an integral locking extension having locking engagement with the panel from

which it is cut to hold the flap in sealing relation to said aperture and opening.

3. A window device for a container having an inspection opening thereon, said device comprising a flexible member subdivided by a transverse fold line into a pair of inner and outer panels adapted to be folded on one another and marginally secured to said container over said opening, said inner panel having an inspection aperture therein and said outer panel having a hinged closure flap therein, said flap in the folded condition of said device overlapping said fold line at a margin of the device and having a laterally enlarged tab portion lockingly engageable beneath said outer panel.

4. A window device for a container having an inspection opening therein, said device comprising a flexible member subdivided by a transverse fold line into a pair of inner and outer panels adapted to be folded on one another and marginally secured to said container over said opening, said inner panel having an inspection aperture therein and said outer panel having a hinged closure flap therein, said flap in the folded condition of said device overlapping said fold line at a margin of the device and having a laterally enlarged tab portion which is foldable onto the flap and lockingly engageable beneath said outer panel.

5. A window device for a container having an inspection opening therein, said device comprising a flexible member subdivided by a transverse fold line into a pair of inner and outer panels adapted to be folded on one another and marginally secured to said container over said opening, said inner panel having an inspection aperture therein in register with said opening in said folded condition and said outer panel being slitted to partially sever a closure flap therefrom, said flap being hingedly connected to said outer panel and in the folded condition of said device overlapping the margin of the device defined by said fold line.

6. A window device for a container having an inspection opening therein, said device comprising a flexible member subdivided by a transverse fold line into a pair of inner and outer panels adapted to be folded on one another and marginally secured to said container over said opening, said inner panel having an inspection aperture therein in register with said opening in said folded condition and said outer panel being slitted to partially sever a closure flap therefrom, said flap being hingedly connected to said outer panel and in the folded condition of said device overlapping the margin of the device defined by said fold line, and transparent sheet material marginally secured to said member between said panels to cover said aperture.

7. A window device for bags and like contain-

ers provided with an inspection opening, comprising a flexible sheet-like member folded on itself to provide superposed panels connected by a fold line on one side thereof, said member being slitted to provide a closure flap hinged to one of said panels and provided with a locking tab at the free end thereof opposite its hinge to said one of the sections, said panels defining a pocket therebetween and said tab having an enlarged end cut from the other of said panels which is slidably engageable in said pocket, said flap being normally held removably to said one of said panels by connecting increments of the material.

8. A blank for a window device of the type described comprising a flexible sheet-like member adapted to be subdivided into a pair of panels by a transverse line of fold, one of said panels being slitted within the marginal limits thereof to define a closure flap hinged thereto for swinging movement, said flap including a tab portion adjacent the free end thereof which extends across said line of fold and is at least in part cut from the material of the other panel, said tab portion having laterally extending ears which are bendable and retainingly engageable between said panels when the latter are superposed by folding on said line of fold, but normally overlying said line in the plane of said flap.

9. A blank for a window device of the type described comprising a flexible sheet-like member adapted to be subdivided into a pair of panels by a transverse line of fold, one of said panels being slitted within the marginal limits thereof to define a closure flap hinged thereto for swinging movement but normally partially connected to said panel other than by said hinge, said flap including a tab portion adjacent the free end thereof which extends across said line of fold and is at least in part cut from the material of the other panel, said tab portion having laterally extending ears which are bendable and retainingly engageable between said panels when the latter are superposed by folding on said line of fold, but normally overlying said line in the plane of said flap.
